S. USTICK.
BRICK MACHINE.

No. 10,777.

Patented Apr. 18, 1854.

UNITED STATES PATENT OFFICE.

STEPHEN USTICK, OF PHILADELPHIA, PENNSYLVANIA.

BRICK-MACHINE.

Specification forming part of Letters Patent No. 10,777, dated April 18, 1854; Antedated November 15, 1853.

To all whom it may concern:

Be it known that I, STEPHEN USTICK, of the city and county of Philadelphia and State of Pennsylvania, have invented a new 5 and useful Improvement in Brick-Machines; and I do hereby declare that the following is a full, clear, and exact description of the construction and operation of the same, reference being had to the annexed drawings, forming part of this specification, in which—

Figure 1 is a plan of the machine. Fig. 2 is a side elevation of the same. Fig. 3 is a vertical section on line x x of Fig. 1. 15 Fig. 4 is an end elevation of the machine. Fig. 5 is a rear view of the movable piston e . Fig. 6 is a top view of same.

Similar characters of reference in the several figures denote the same part of the 20 machine.

The nature of my invention consists in the employment of a combination of movable and fixed pistons and movable mold boxes, arranged and operating as will be 25 hereafter described, together with an arrangement for receiving and delivering the molded brick, and also a combination of devices for lubricating the faces of the pistons after the delivery of each brick for 30 preventing the adhesion of the clay to said pistons.

To enable others skilled in the art to make and use my invention I will proceed to describe its construction and operation.

35 In the drawing A and B are the top and bottom pieces of the frame, and C the vertical frame pieces, bolted fast between A and B. Resting in the guides b b (Fig. 4) and capable of a reciprocating motion in 40 the same are the molds a (Fig. 3) having in their upper portions the chambers a' , which receive the clay from the hoppers C' before it is pushed into the condensing part of the mold. On the lower side of the 45 molds a are the friction wheels c , which are pressed upon by the cam wheel d , to give a reciprocating motion to the molds, as and for the purposes hereafter to be described.

The movable pistons e are of the form 50 shown in Figs. 5 and 6, their slides e' working in grooves in the inner faces of the side pieces f , by the action of the cam m upon the rollers g in their rear extremities, or of the cams h and i (Fig. 1) on the rollers g' 55 beneath the pistons. The cams i , which

withdraw the pistons e to admit the clay into the condensing boxes of the molds, are movable about their attachments i' , by means of the oblique wheels j on the rod k , which fitting between pins on the under side 60 of the cams i (Fig. 2) move the cams as the rod k is turned by the rotation of the head wheels l , thus regulating the quantity of clay taken into the molds a .

The cams m and d are secured to the 65 shaft n , which is rotated by any suitable arrangement of gearing. The stationary pistons p are bolted to the frame of the machine and by the movement of the mold condense the clay on the side nearest them, 70 as will be hereafter described.

Fastened to the exterior of the cam wheel d are the hands q , on which the bricks drop when pushed from the molds. Beneath them are the wheels r , which by running upon the inclined planes s elevate the hands to the level of the bottom of the molds to receive the brick and afterward lower the same to the level of the tables t , on which the bricks are discharged. Bolted fast to the hands q , are the lubricating boxes u , having their sides which pass between the faces of the pistons constructed of leather or other absorbing substance tacked on the ends and bottom of the boxes, 80 which are of wood or other suitable material. The tops of the boxes are either left open or covered with a hinged or other fastened lid. These boxes being filled with oil gently lubricate the faces of the pistons as they pass between them by the ooze through the leather sides. Besides oiling the pistons the front faces of the boxes push the bricks from between said pistons as the hands q rise to receive them. The bricks are delivered upon the tables t from the hands q , by the pressure of the fingers x against them, said fingers having a lateral movement by reason of the pressure of the cams y y' on the friction rollers z of the slides w , causing said slides to move over the guides v , fastened beneath the cam wheel d .

In the under sides of the molds a are cross grooves a' for the escape of air condensed during the pressure of the bricks. These grooves are kept open by scrapers b' on the cam wheel d , which pass through them at the time of greatest condensation.

I have represented but two molds in the machine, but design in practice to employ 110

a series of molds with their pistons radiating from the center shaft n , an even number being generally employed, so that equal pressure shall be produced on opposite sides 5 of the cams. The several hoppers I connect at top with an annular trough, from which they receive their supply of clay.

The operation of my machine is as follows:—Motion is communicated to the shaft 10 n revolving the cam wheel d and cam m in the direction of the arrow, causing the series of cams on the wheel d to give a reciprocating motion to the molds a , and the cams m , h and i a similar motion to the 15 pistons e , with the effect below described. Commencing with the cam l of the wheel d (Fig. 1) on the line xx , the molds a have their extreme outward position, the extremity of the said cam pressing against the 20 roller c . The hopper c' is then directly over the receiving chamber a'' and space between the pistons p and e . At this time the condensing chamber R receives its 25 charge of clay from the hopper c' , the quantity received being well packed by the weight of the entire head of clay in the hopper, the quantity, which depends upon the position of the piston e , being regulated by the position of the cam i , against 30 the rear extremity of which the friction roller g' presses when the wheel d has the above described position. This adjustment of the cam i , as above stated, is regulated by the revolution of the oblique wheel j , 35 which turning between the pins on the under face of the cam to the desired position to admit of the reception of the required quantity of clay. From the point 1 the mold a moves inward until the point 2 40 reaches the wheel c , at which time the receiving chamber a'' has passed over the upper surface of the piston e , cutting off the clay in the condensing chamber R from the supply above. Between the points 45 2 and 4 the piston e is moved into the mold to condense the clay by the cam m bearing against the friction roller g , while at the same time the mold a is moved outward over the stationary piston p with half the 50 velocity of the piston e , which effects an equal pressure by both moving and stationary pistons and makes the bricks of equal solidity on both sides. When the point 3 is on the line xx the several parts 55 have the positions shown by Fig. 3. The cleaner b' passes through the opening a' in the bottom of the mold at the time of nearly maximum compression, causing the condensed air to pass out during the operation, 60 thus preventing the after cracking of the brick. The pressure of the brick being completed at the point 4, the mold is moved toward the center of the machine as the cam from 4 to 5 passes the line xx , during 65 which time the roller g bears against the

concentric portion 9 of the cam wheel m , to retain the pressure against the faces of the brick, in order that the condensed air that may have remained in them notwithstanding the operation of the discharge air groove a' , as described) may escape when their edges are exposed to the atmosphere, before the pressure of the pistons is taken off their faces, to avoid the cracking of the brick. As the point 5 passes the line xx , 70 the extremity of the cam h acting on the roller g' , draws the piston e slightly toward the center of the machine, and the brick falls upon the hand g , which at that time is directly under it, the oily sides of 75 the box u wiping the faces of the pistons to prevent the adhesion of the following made bricks. From the point 5 to the point 1 the cam wheel d carries the mold a to its extreme outer position, and the cam i withdraws the piston e the required distance for 80 the supply of clay, bringing the machine in the position at which the description of its operation commenced. After receiving the brick the hand g descends to nearly the level 85 of the table t , by the roller r running down the inclined plane s , and the cam y' pressing against the friction wheel z pushes out the slide w and with it the finger x , which gently slides the brick upon the table t , whence it 90 is removed by the operatives. The cam y withdraws the slide w and finger x .

The operation of making a single brick has been described above, though any reasonable number can be produced by an increase of pistons, &c., the movement of the 100 opposite pistons being simultaneous.

Instead of the molds and pistons vibrating in stationary frames and the cams revolving upon a central shaft, I claim the 105 right of reversing the order of arrangement by making the cam wheels d and m stationary on a center shaft supported by a suitable frame work and placing the molds and pistons on a revolving wheel, the stationary pistons being firmly secured to the rim of the wheel, as in such arrangement the same effects would be produced substantially in all the operations of the molds and pistons. 110

In working the clay with the ordinary degree of moisture it has when worked in dry clay machines the arrangement of the hoppers as represented would be adequate to secure the filling of the molds. But should it be desired to work it so moist that the molds would not readily fill I design using knives, placed spirally on a shaft, to force the clay down the hoppers. In such case that part of the hopper in which the knives revolve should be circular. As a similar arrangement of hopper is used in tempered clay machines, a particular description is not given here. 125

I do not claim in general the combination 130

of the reciprocating mold boxes with the stationary and movable pistons; nor do I claim merely feeding the clay through the side of the mold box at right angles to the line of motion of the piston, as these features exist in other machines; but

What I do claim as my invention and desire to secure by Letters Patent, is—

1. The arrangement substantially as herein described of the mold box with the fixed and movable pistons, whereby, by its motion in the line of motion of the piston, it is made to perform the function of feeding the clay between the pistons, shutting it off from communication with the hopper, and discharging the brick.

2. I claim the apparatus for receiving and delivering the brick consisting of the hand

g, table t, and finger x arranged and operating substantially as described.

3. I claim the arranging on the cam wheel a, the oil boxes u for lubricating and cleaning the faces of the pistons.

4. I claim the withdrawing the condensed air from the mold while the pressure is produced by the groove a' and scraper b' or other equivalent devices substantially as herein before set forth.

In testimony whereof, I have hereunto signed my name before two subscribing witnesses.

STEPHEN USTICK. [L. s.]
